LID FOR A LOAD ON AN INDUSTRIAL PLATFORM PALLET OR THE LIKE

Charles G. Cardwell and Morris E. Speck, Bartlesville,
Okla., assignors to Phillips Petroleum Company, Bartles-
ville, Okla.

Filed June 24, 1974, Ser. No. 482,256

Term of patent 14 years

Int. Cl. D9—99

U.S. Cl. D12—60

FIG. 1

FIG. 2

FIG. 3

FIG. 4

FIG. 5

FIG. 6

FIG. 7

FIG. 1 is a top plan view of a lid for a load on an industrial platform pallet or the like, showing our new design;

FIG. 2 is a side elevational view thereof, the opposite side being the same as the side shown herein;

FIG. 3 is a front elevational view thereof, the rear being the same as the front shown herein;

FIG. 4 is an elevational view in cross section taken along line 4-4 of FIG. 1;

FIG. 5 is an elevational view in cross section taken along line 5-5 of FIG. 1;

FIG. 6 is an elevational view in cross section taken along line 6-6 of FIG. 1; and

FIG. 7 is an elevational view in cross section taken along line 7-7 of FIG. 1.

We claim:

The ornamental design for a lid for a load on an industrial platform pallet or the like, as shown.
